(57) **CLAIM**

The ornamental design for a cleaning device for pierced openings, as shown and described.

DESCRIPTION

FIG. 1 is a perspective view of a cleaning device for pierced openings, showing our new design;

FIG. 2 is a front elevational view thereof;

FIG. 3 is a rear elevational view thereof; and,

FIG. 4 is a left-side elevational view thereof, the right-side elevational view being a mirror image thereof.

The broken lines showing an ear in FIG. 1 depict environmental matter and form no part of the claimed design.
